ELECTRICAL CONNECTOR

John A. Toedtman, St. Louis, Mo., assignor to Jasper Blackburn Corporation, St. Louis, Mo., a corporation of Missouri

Filed Nov. 19, 1962, Ser. No. 238,398
7 Claims. (Cl. 339—109)

This invention relates generally to improvements in an electrical connector, and more particularly to an improved structural arrangement that facilitates the installation of such connector to a "hot" line.

It is an important object of the invention to provide a parallel-groove connector that enables a tap wire to be held securely, yet temporarily, while the connector is operatively attached to both the tap wire and a through main wire.

Another important objective is achieved by the provision of a set screw attached and carried by one of the body sections, the set screw being adapted to hold the tap wire to the same body section in a tap wire groove located between a pair of body sections, and by the provision of fastening means interconnecting the body sections and selectively closing the body sections onto the tap wire and main wire while the tap wire is held temporarily in place by the set screw.

Still another important object is afforded by an end flange on one body section which overlaps the tap wire groove, the end flange having an opening through which the tap wire extends when located in the appropriate groove, the set screw being threadedly attached to the end flange and engaging the tap wire in the opening for retention.

An important object is realized by the provision of a pair of end flanges on one of the body sections which overlap opposite ends of the tap wire groove, each end flange having an opening adapted to receive the tap wire and position it in the tap wire groove. The end flanges preclude the tap wire from falling downwardly out of the groove, while the set screw, in addition, prevents the tap wire from being withdrawn endwise from the connector.

Another important object is provided by resilient means between the body sections tending to urge the body sections apart, and by a guide means interconnecting one side of the body sections and enabling relative swinging and shifting movement of the body sections toward or away from each other upon actuation of the fastening means.

Yet another important objective is achieved by the provision of a bolt that constitutes the fastening means, and by the provision of means on one body section which provides a chamber for lubricant into which the end of the bolt moves upon bolt actuation, the lubricant conditioning the bolt for easy operation at all times.

An important object is realized by threadedly attaching the bolt to one body section and freely passing the bolt through a slot formed in the other body section, the bolt moving relatively along the slot as the body sections swing and shift about the guide means connection.

Other important advantages are obtained by the provision of a curvilinear camming surface on one of the body sections which coacts with the bolt to move the body sections together easily upon tightening of the bolt.

Another important objective is to provide a parallel-groove connector that is simple and durable in construction, economical to manufacture and assemble, highly efficient in operation and which can be easily installed by anyone with only a minimum of instruction.

The foregoing and numerous other objects and advantages of the invention will more clearly appear from the following detailed description of a preferred embodiment,

2

particularly when considered in connection with the accompanying drawing, in which:

FIG. 1 is a top plan view of the electrical connector, illustrating the main wire and tap wire in broken lines;

5 FIG. 2 is an end elevational view illustrating the tap wire retained temporarily in place;

FIG. 3 is a side elevational view as seen from the left of FIG. 2;

10 FIG. 4 is a cross sectional view as seen along line 4—4 of FIG. 3, illustrating the connector as clamped securely on both the main wire and tap wire, and

FIG. 5 is a fragmentary cross sectional view as seen along line 5—5 of FIG. 4.

15 Referring now by characters of reference to the drawing, it is seen that the electrical connector is of the parallel-groove type adapted to connect operatively a tap wire 10 with a through main or "hot" wire 11.

20 From FIGS. 2 and 4, it is seen that the upper body section generally referred at 12 is provided with a longitudinal, substantially arcuate seat 13 on its bottom. The seat 13 extends endwise of the connector and is located at one side. At the opposite side of the connector, the upper body section 12 is provided with a longitudinal, substantially arcuate seat 14 on its bottom. For reasons 25 which will appear later, it will be noted that the arcuate seat 14 is larger than its laterally spaced, parallel, yet co-operating seat 13.

Located in the upper body section 12 between the longitudinal seats 13 and 14, is a threaded vertical bore 15.

30 To facilitate positioning of the upper body section 12 upon assembly, the body section 12 is provided with downwardly depending shoulders 16. These shoulders 16 are located on opposite sides of the vertical bore 15 and are located internally of the connector.

35 In addition, the upper body section 12 includes a pair of end flanges 17 and 18 that overlap the ends of the arcuate seat 13. Each of the end flanges 17 and 18 is provided with an opening 20 aligned with arcuate seat 13, the tap wire 10 extending through the opening 20. It will 40 be noted that when the tap wire 10 is located in the end flange opening 20, the tap wire 10 is carried by the upper body section 12, the end flanges 17 and 18 precluding the tap wire 10 from falling downwardly out of the connector.

45 One of the end flanges 18 is provided with an enlarged boss portion 21 immediately adjacent its associated opening 20. A set screw 22 is threadedly attached and carried by the boss portion 21, the set screw 22 extending into the opening 21 and operatively engaging the tap wire 10 to hold the tap wire 10 selectively against the seat 13 as is illustrated in FIG. 2.

50 The electrical connector includes a cooperating lower body section referred to generally at 23. The lower body section 23 is provided with an upwardly facing longitudinal arcuate seat 24. It will be importantly noted 55 that the body seats 13 and 24 formed respectively in the cooperating body sections 12 and 23 are aligned vertically to provide a tap wire groove therebetween as is best seen in FIGS. 2 and 4. When the body sections 12 and 23 are assembled, the tap wire groove is adapted to receive 60 the tap wire 10.

55 The opposite side of body section 23 includes an upwardly facing, longitudinal arcuate seat 25. The substantially arcuate seat 25 is larger than its laterally spaced, parallel, yet associated arcuate seat 24. Importantly, 65 it will be noted that the arcuate seats 14 and 25 formed respectively in the cooperating body sections 12 and 23 are aligned vertically upon assembly of the body sections 12 and 23 so as to form a main wire groove as is best seen in FIGS. 2 and 4, the main wire groove being particularly adapted to receive the main wire 11.

That portion of the lower body section 23 intermediate the arcuate seats 24 and 25 is provided with a pair of

upwardly extending end shoulders 26 that fit within the upper body section 12 and are located closely adjacent the end flanges 17 and 18. This structural arrangement precludes relative longitudinal movement of the body sections 12 and 23 in an endwise direction.

Formed transversely in the lower body section 23 between the arcuate seats 24 and 25 is a slot 27 that is aligned vertically with the threaded bore 15 when the body sections 12 and 23 are assembled. The purpose and function of slot 27 will be apparent upon subsequent description of parts.

The lower body section 23 is provided with a curvilinear camming surface 30 on its underside. As will appear later, this camming surface 30 facilitates the positioning of the lower body section 23 relative to the upper body section 12.

Immediately below the arcuate seat 24, each end of the lower body section 23 is provided with a recess that provides an inverted L-shaped shoulder 31. Engaging each of the shoulders 31 is an in-turned shoulder 32 formed on each of the end flanges 17 and 18. As will appear, the cooperating shoulders 31 and 32 constitute a guide means interconnecting the upper and lower body sections 12 and 23.

When the lower body section 23 is loosened and swung open as is illustrated in FIG. 2, the shoulders 31 seat on the in-turned flange shoulders 32 to provide a connection about which the lower body section 23 swings. When the lower body section 23 is moved to a closed position as will be described later, the lower body section 23 swings upwardly about the connection formed by engaging shoulders 31 and 32, and subsequently the lower body section 23 shifts upwardly toward the upper body section 12, at which time the horizontal portion of each inverted L-shaped shoulder 31 disengages from its coacting in-turned flange shoulder 32. However, it will be noted that during this upward shifting movement of the lower body section 23, that the in-turned flange shoulders 32 engage the relatively vertical portions of the inverted L-shaped shoulders 31 to guide the lower body section 23 in such movement to assure that the tap wire 10 and main wire 11 are clamped securely in place.

Depending from each end of the lower body section 23 is a lug 33, the lugs 33 cooperating with a "hot" control stick (not shown) for placement of the connector, and particularly for location of the connector to receive the main wire 11 in the main wire groove between the body sections.

The fastening means interconnecting the body sections 12 and 23 includes a bolt 34 that extends upwardly freely through the slot 27 formed in lower body section 23 and threadedly engages the bore 15 formed in the upper body section 12. An eye member 35 is attached to the lower end of bolt 34. A suitable tool (not shown) can be advantageously connected to the eye member 35 to turn the bolt 34 incident to closing or opening the body sections 12 and 23.

A pair of washers 38 and 39 are disposed about the bolt 34 and located between the eye member 35 and the underside of the lower body section 23. Washer 38 is flat while washer 39 is dished downwardly, so that upon tightening, the washer 39 will exert a resilient axial pressure on the bolt 34 and particularly between the coacting threads in bore 15 to provide a secure attachment.

As will appear, upon tightening the bolt 34, the bolt 34 will urge the lower body section 23 upwardly toward the upper body section 12 very easily. Upon tightening the bolt 34, the camming surface 30 tends to swing or laterally adjust the position of the lower body section 23 to accommodate the particular sizes of the tap wire 10 and main wire 11 and to distribute the clamping forces on such wires so as to hold the wires securely between the body sections. To permit this swinging movement and slight lateral adjustment of the lower body section 23, the bolt 34 moves relatively along the slightly elongated slot 27.

Formed integrally on the top side of upper body section 12 is a substantially cylindrical member 36 providing a chamber 37 into which the upper end of bolt 34 moves. A lubricant 40 is placed in the chamber 37. The upper end of cylindrical member 36 is closed by lid 41 to seal the lubricant 40 in such chamber 37. The lubricant 40 lubricates the threads on the bolt 34 and makes it easy to turn at all times.

Located between the body sections 12 and 23 and disposed about the bolt 34 is a compression spring 42 constituting a resilient means. The spring 42 tends to urge the body sections 12 and 23 apart.

It is thought that the installation of the electrical connector and the functional results and advantages have become fully apparent from the foregoing detailed description of parts, but for completeness of disclosure, such installation will be briefly set forth.

First, the electrical connector is assembled by placing the body sections 12 and 23 in superimposed relation, one above the other, as is shown in FIGS. 2 and 4, with the guide shoulders 32 interfitting the coacting guide shoulders 31, with the seats 13 and 24 aligned to form the tap wire groove and with the arcuate seats 14 and 25 aligned to form the main wire groove.

Then the bolt 34 is inserted upwardly through the slot 27 into the threaded bore 15 to hold the body sections together. The bolt 34 is adjusted so that the lower body section 23 is swung downwardly to its fully open position as is illustrated in FIG. 2 to permit the insertion of the tap wire 10 and the main wire 11.

For "hot" line installation, the tap wire 10 is inserted through the openings 20 in the end flanges 17 and 18 of the upper body section 12, and hence is disposed in the arcuate seat 13. The tap wire 10 is clamped against seat 13 and thereby secured to the upper body section 12 by threadedly tightening the set screw 22 onto the tap wire 10. It is seen that the set screw 22 holds the tap wire 10 to the upper body section 12 temporarily incident to the permanent installation.

A control stick (not shown) is used to grip the lugs 33 and raise the electrical connector into position for operative connection to the "hot" main wire 11. The connector is manipulated so that the main wire 11 is inserted between the body sections 12 and 23 and into the main wire groove. After the main wire 11 is located in the main wire groove, another suitable tool is utilized to tighten the bolt 34, and hence clamp the body sections 12 and 23 together on both the tap wire 10 and main wire 11.

As the bolt 34 is threadedly tightened, the bolt 34 swings the lower body section 23 upwardly toward the upper body section 12 about the guide shoulder connection 31-32 and subsequently shifts the lower body section 23 upwardly as permitted by the interfitting guide shoulders 31 and 32. The body sections 12 and 23 are urged together while the tap wire 10 is temporarily held in place against the upper body section 12 by the set screw 22. As explained previously, the body section 23 adjusts itself automatically to accommodate the sizes of the wires involved.

Of course, the body sections are moved together against the loading of the compression spring 42.

Upon tightening, the upper end of the bolt 34 moves into the lubricant chamber 37.

After tap wire 10 and main wire 11 have been clamped securely between the body sections 12 and 23 upon threadedly tightening of bolt 34, the tool is disconnected from the eye member 35 and the control stick is removed from the lugs 33.

To disconnect the electrical connector, substantially the reverse sequence of the steps described above is carried out. For example, the bolt 34 is loosened which allows the lower body section 23 to move and swing downwardly under the compressive loading of spring 42 to the position illustrated in FIG. 2. A control stick attached to the lugs 33 can be then utilized to remove the connector from the main wire 11. If desired, the tap

wire 10 can be easily removed by loosening the set screw 22 and withdrawing the tap wire 10 endwise through the end flange openings 20.

Although the invention has been described by making detailed reference to a single preferred embodiment, such detail is to be understood in an instructive, rather than in any restrictive sense, many variants being possible within the scope of the claims hereunto appended.

I claim as my invention:

1. An electrical connector comprising:

- (a) a pair of body sections, said body sections having a tap wire groove and a main wire groove therebetween,
- (b) means on one of said sections by which a tap wire is clamped to said one body section in the tap wire groove,
- (c) resilient means carried by and between said body sections tending to urge said body sections apart,
- (d) fastening means interconnecting said body sections and selectively closing the sections against the loading of resilient means onto a main wire located in the main wire groove and onto the tap wire located in the tap wire groove, and
- (e) the body sections including shoulders, the shoulder of one body section seating on the shoulder of the other body section under loading of the resilient means to provide a connection about which the one body section swings upon tightening of the fastening means.

2. An electrical connector comprising:

- (a) a pair of body sections, said body sections having a tap wire groove and a main wire groove therebetween,
- (b) means on one of said sections by which a tap wire is clamped to said one body section in the tap wire groove,
- (c) resilient means carried by and between the body sections tending to urge the body sections apart,
- (d) fastening means interconnecting said body sections and selectively swinging and moving the body sections onto a main wire located in the main wire groove and onto the tap wire located in the tap wire groove, and
- (e) one body section including an out-turned shoulder, and the other body section including an in-turned shoulder on which the out-turned shoulder seats under the loading of the resilient means to provide a connection about which the one body section swings upon tightening of the fastening means.

3. An electrical connector comprising:

- (a) a pair of body sections, said body sections having a tap wire groove and a main wire groove therebetween,
- (b) means on one of said sections by which a tap wire is clamped to said one body section in the tap wire groove,
- (c) resilient means carried by and located between said body sections tending to urge said body sections apart,
- (d) fastening means interconnecting said body sections and selectively swinging and shifting the body sections toward each other against the loading of said resilient means onto a main wire located in the main wire groove and onto the tap wire located in the tap wire groove, and
- (e) one body section including an inverted substantially L-shaped shoulder, and the other body section including an in-turned shoulder on which the substantially L-shaped shoulder seats under loading of the resilient means to provide a connection about which the one body section swings upon tightening of the fastening means until the main wire is engaged, the shoulders unseating yet engaging laterally to guide the one body section on a shifting movement under loading of the resilient means in order to engage

the tap wire upon continued tightening of the fastening means.

4. An electrical connector comprising:

- (a) a pair of body sections, said body sections having a tap wire groove and a main wire groove therebetween,
- (b) means on one of said sections by which a tap wire is clamped to said one body section in the tap wire groove,
- (c) resilient means carried by and located between said body sections tending to urge said body sections apart,
- (d) fastening means interconnecting said body sections and selectively swinging and shifting the body sections toward each other against the loading of said resilient means onto a main wire located in the main wire groove and onto the tap wire located in the tap wire groove,
- (e) one body section including a pair of inverted substantially L-shaped shoulders, and the other body section including a pair of in-turned shoulders on which the L-shaped shoulders seat under loading of the resilient means to provide a connection about which the one body section swings upon tightening of the fastening means until the main wire is engaged, the in-turned shoulders engaging the relatively upright portions of the inverted L-shaped shoulders to guide the one body portion in a shifting movement to engage the tap wire upon continued tightening of the fastening means, and
- (f) one of said body sections including a curvilinear camming surface engaging the fastening means to swing and shift the body sections together easily upon tightening of said fastening means.

5. An electrical connector comprising:

- (a) a pair of body sections, said body sections having a tap wire groove and a main wire groove therebetween,
- (b) means on one of said sections by which a tap wire is clamped to said one body section in the tap wire groove,
- (c) a bolt operatively interconnecting said body sections between said grooves,
- (d) a resilient means about the bolt and carried by and between the body sections tending to urge said body sections apart, and
- (e) the body sections including shoulders at one side of the bolt adjacent the tap wire groove, the shoulder of one body section seating on the shoulder of the other body section under loading of the resilient means to provide a connection about which the one body section swings upon tightening the bolt until the one body section engages the main wire, the shoulders engaging laterally to guide the one body section in a shifting movement to engage the tap wire upon continued tightening of the bolt.

6. An electrical connector comprising:

- (a) a pair of body sections, said body sections having a tap wire groove and a main wire groove therebetween,
- (b) means on one of said sections by which a tap wire is clamped to said one body section in the tap wire groove,
- (c) a bolt operatively interconnecting said body sections between said grooves, the bolt being threadedly attached to one body section, the other body section being provided with a slot through which the bolt freely extends,
- (d) a compression coil spring about the bolt and carried by and between the body sections tending to urge said body sections apart, and
- (e) one body section including a pair of laterally spaced out-turned shoulders adjacent the tap wire groove at one side of the bolt, the other body section including a pair of in-turned shoulders on which

the out-turned shoulders seat under loading of the spring to provide a connection about which the one section swings as the bolt is tightened until the main wire is engaged, the shoulders slidably engaging to guide the body sections in a shifting movement of the one body section toward the other body section to engage the tap wire upon continued tightening of the bolt.

7. An electrical connector comprising:

- (a) an upper and a lower body section, said body sections having a tap wire groove and a main wire groove therebetween,
- (b) means on the upper sections by which a tap wire is clamped to the upper body section in the tap wire groove,
- (c) a bolt operatively interconnecting said body sections between said grooves, the bolt being threadedly attached to the upper body section, the lower body section being provided with a slot through which the bolt slidably extends,
- (d) a compression coil spring about the bolt and carried by and between the body sections tending to urge said body sections apart, and
- (e) the lower body section including a pair of inverted substantially L-shaped shoulders laterally spaced and located on the tap wire groove side of the bolt, the

5

15

20

25

upper body section including a pair of laterally spaced in-turned shoulders on which the substantially L-shaped shoulders seat under loading of the spring to provide a connection about which the lower body section swings upon tightening of the bolt until the lower body section engages the main wire, the in-turned shoulders engaging the relatively vertical portions of the inverted L-shaped shoulders to guide the lower body section in an upwardly shifting movement toward the upper body section to engage the tap wire upon continued tightening of the bolt,

- (f) the bolt moving relatively along said slot as the body sections swing about and shift on the said inter-fitting shoulders.
